(No Model.)

J. GARDNER.

HOLDER FOR PACKING CARTRIDGES.

No. 285,992.

Patented Oct. 2, 1883.

UNITED STATES PATENT OFFICE.

JOHN GARDNER, OF NEW HAVEN, CONNECTICUT, ASSIGNOR TO THE WINCHESTER REPEATING ARMS COMPANY, OF SAME PLACE.

HOLDER FOR PACKING CARTRIDGES.

SPECIFICATION forming part of Letters Patent No. 285,992, dated October 2, 1883.

Application filed August 13, 1883. (No model.)

To all whom it may concern:

Be it known that I, JOHN GARDNER, of New Haven, in the county of New Haven and State of Connecticut, have invented a new Improvement in Packing Cartridges; and I do hereby declare the following, when taken in connection with accompanying drawings and the letters of reference marked thereon, to be a full, clear, and exact description of the same, and which said drawings constitute part of this specification, and represent, in—

Figure 1, a top of plan view; Fig. 2, a side view; Fig. 3, a longitudinal section through the locking mechanism and one of the apertures enlarged; Figs. 4, 5, and 6, sectional side views to illustrate the method of employing the holders in the packing of cartridges; Fig. 7, the supporting-frame on a reduced scale.

This invention relates to an improvement in apparatus for arranging cartridges in packages. Cartridges are usually packed in paper boxes or cases containing fifty or one hundred. The larger cartridges are arranged in the box, one half of them standing upon their head in the bottom of the box, the other half introduced between them point downward, so that the heads stand upward, and thus all cartridges stand with their axes parallel; but in the case of the smaller cartridges they are placed in the box without any particular arrangement. Before placing in boxes the bullets are greased, and when placed in the box without some arrangement the cartridge-shells come in contact with the greased portion of the bullet, and take therefrom more or less of the grease, so that the cartridge-cases are not only soiled, but oxidation soon follows, rendering it many times difficult to introduce them into the chamber for firing, and also making them unpleasant to handle. The arrangement of the larger cartridges, as before described, has usually been made by hand. Such hand operation to arrange the smaller sizes would be too expensive. The invention of Thomas G. Bennett, June 27, 1882, No. 260,153, obviated to a considerable extent the expense of thus packing cartridges, particularly as to the larger sizes. In that invention a pair of plates is employed, each perforated corre-

sponding to the size of the cartridges under 50 the head, the holes in one plate being intermediate between the holes in the other. The cartridges are introduced through the holes in the plates, suspended by their heads. One plate thus filled is inverted. Then the second 55 plate, with its cartridges hanging downward, is placed over the first plate of cartridges, and the cartridges in the second plate passed between those in the first plate, and then the plates and cartridges are introduced into the 60 package. While this invention is well adapted to the larger sizes of cartridges, it is too expensive for the smaller sizes. In greasing the smaller classes of cartridges, as in the process of Burns as patented September 12, 1882, No. 65 264,237, the cartridges are arranged through holes in a plate, bullets downward, and suspended in the plate by the head, and while in this condition the bullets are greased in a 70 mass.

The object of my invention is to avoid the handling of the cartridges after they have been thus greased, and introduce them directly to their boxes, arrange them therein one half with heads downward, the other half between 75 the first half and with heads upward, and at the same time avoid leaving the plates in the boxes, as in the Bennett invention; and the invention consists in a holder for cartridges, composed of a pair of plates, each perforated 80 with holes of substantially the diameter of the head of the cartridge, and so that the holes in one plate will register with the holes in the other plate, the one plate movable upon the other, whereby the holes in the one plate may 85 overlap the holes in the other plate sufficiently to suspend the cartridge by the head and prevent its dropping through the hole until the plates are moved to bring the holes into registering or concentric position, when the cartridge-heads are free to pass through the holes, 90 and as more fully hereinafter described.

The holder in which the cartridges are arranged consists of two plates, *a b*. These plates are perforated alike, the hole *d* in the one corresponding in size to the hole *e* in the other, and each hole of substantially the diameter or a little larger than the head of the car-

tridge. The holes are arranged in groups, as seen in Fig. 1, and are distant from each other little more than the diameter of the head of the cartridge, the several groups in extent corresponding, substantially, to the size and shape of the box or package into which the cartridges are to be introduced. As seen in Fig. 5, the plates are constructed for four groups of cartridges—that is to say, cartridges for four boxes. These plates are arranged one upon the other and secured together by screws through a slot, *h*, in one plate into the other plate, and so that the one plate, *b*, may be moved upon the other plate, *a*, in parallel planes, and so as to bring the holes into a concentric or registering position, as seen in broken lines, Fig. 3, or moved so as to cause that portion of one plate adjacent to its holes to overlap the corresponding portion of the holes in the other plate, as seen in Fig. 3, this overlapping serving to reduce the aperture through the two plates to about the diameter of the cartridge-shell below the head, as seen in Fig. 3; hence when thus overlapped a cartridge passed through the aperture will hang by its head, as seen in Fig. 3. The plates thus moved into position to contract the apertures are locked by a latch, *A*. This latch is hinged to the one plate, *a*, and so that its nose passes through corresponding holes *l* in the two plates, as seen in Fig. 2. The latch is provided with a finger-piece, *B*, by which it may be withdrawn, as seen in broken lines, Fig. 3, and with a spring, *C*, the action of which is to force the latch into its locking position. When the plates are thus locked together, the cartridges are thrown in mass upon them and then agitated to constantly rearrange the cartridges, causing a portion of them to pass down through the openings point downward, and until all the apertures are filled. When the holder is thus filled, the bullets may be dipped for greasing as in the Burns or other suitable process. Then a board, *D*, is placed upon the upper side—that is, upon the heads of the cartridges—and the plates with the cartridges inverted, as seen in Fig. 4, the lower series of cartridges representing the plates and cartridges thus inverted. Then a second pair of plates of like construction and character is filled with cartridges and set upon the first, as seen in Fig. 4, point downward, the cartridges in that plate passing down between the cartridges in the first or inverted plate. This done, the latch *A* is disengaged and the plates are moved to bring the holes into a concentric position, as seen in broken lines, Fig. 3, and when so brought into registering position they are lifted from over the heads of the cartridges, leaving the cartridges standing, as in Fig. 5. Then the box *E* is placed over the mass of cartridges, as seen in Fig. 5, and then the box, the lower plate, and the board *D* are inverted, bringing the first pair of plates uppermost, as seen in Fig. 6. This done, the board is removed, and the plates, which now suspend the inverted car-

tridges, are removed, and the cartridges stand in their box alternately head up and down.

The holder, as before stated, may have several groups of cartridges, each group corresponding to one box. It will be understood that the holes in one pair of plates will be arranged in a position intermediate between the holes in another plate, the one plate receiving the first groups, the other plate receiving the second groups in positions intermediate between those of the first groups, as in the plates of the Bennett patent.

I find it convenient to place over the first inverted groups a frame, *F*, the openings of which correspond to the internal dimensions of the boxes, and so that when the second groups are placed upon the first, as seen in Fig. 4, the mass will be embraced by the opening in the frame, and thus will be supported after the first plate has been removed, and until the box can be set thereon. This frame is shown detached on a reduced scale in Fig. 7. When this holder is employed as the plate to support the cartridges for greasing, as in the Burns patent before referred to, all handling of the cartridges thereafter is avoided, as the operator, in manipulating the plates, takes all the cartridges which are suspended in that plate and leaves them in their respective boxes.

While this invention is designed with special reference to the smaller sizes of cartridges, it may be used with great facility in packing larger cartridges, and after the method described in the Bennett patent; and it permits the removing of the plate from the cartridges after they have been placed in their package, instead of leaving it there, as in the Bennett invention.

The invention, while designed with special reference to packing cartridges, may be used for other operations in the process of manufacturing cartridges.

While I prefer to lock the two plates of the holder together, as described, this locking is not essential, as the operator may hold them in their proper relative position during the manipulation.

I claim—

1. The herein-described cartridge-holder, consisting of the two plates *a* *b*, each perforated with holes corresponding, substantially, to the diameter of the head of the cartridge to be held, the one plate movable upon the other, to bring the holes into registering or concentric position or to contract the aperture, substantially as described.

2. The herein-described cartridge-holder, consisting of the two plates *a* *b*, each perforated with holes corresponding, substantially, to the diameter of the head of the cartridge to be held, the one plate movable upon the other, to bring the holes into registering or concentric position or to contract the aperture, and mechanism, substantially such as described, to lock the plates when the aper-

tures are in the contracted condition, substantially as described.

3. A pair of plates arranged one upon the other, the two perforated with holes corresponding, substantially, to the diameter of the head of the cartridges to be held, the one plate movable upon the other, to bring the holes into registering or concentric position or to contract the aperture, as described, the said

perforations formed in groups corresponding to the size of the box or case into which the cartridges are to be introduced, substantially as described.

JOHN GARDNER.
